SCREENING MILL

Carl L. Sidwell and Theodore R. Sidwell, Devertown, Ohio, assignors to Carl L. Sidwell and Theodore R. Sidwell, doing business as Sidwell Brothers, Devertown, Ohio

Application June 11, 1949, Serial No. 98,595

2 Claims. (Cl. 241—76)

1

Our invention relates to a screening mill. It has to do, more particularly, with a screening mill which is of the general type known as ball or rod mills.

It has been the practice in the past to provide ball or rod mills which are composed mainly of a rotating screen or cylinder. However, if the tumbling action of the balls in the cylinder is the only means provided for pulverizing the material in the cylinder, considerable time is required for this operation. This is especially true if the lumps or pieces to be pulverized are large and hard.

It is the main object of our invention to provide a screening ball or rod mill with additional means for quickly and effectively pulverizing the larger lumps or pieces of the material to be ground.

Another object of our invention is to have such additional means so arranged that the finally sized particles must pass through the cylindrical screen of the mill before being discharged from the mill.

Still another object of our invention is to provide a screening mill of the type indicated above which is extremely simple and inexpensive to manufacture but yet which is very effective in quickly pulverizing and sizing the material.

Various other objects will be apparent.

According to our invention we provide a ball or rod mill which includes the usual type of cylindrical screen adapted to contain the balls or rods along with the material to be pulverized by the tumbling action of the balls. The interior of the screen is provided with baffles or plates in the usual way which aid in lifting the material to be pulverized and increase the tumbling action. However, we do not rely merely upon the tumbling action of the balls and material for performing the milling or pulverizing operation. We provide additional means within the cylinder for pulverizing or milling lumps or pieces of selected size but yet which are too large to pass through the cylindrical screen. This additional means comprises milling rolls between which the material is fed. However, sizing means is associated with the rolls for preventing the extremely large lumps from reaching the rolls. This sizing means selects the particles or lumps which are too large to pass through the screen but rejects the extremely large lumps so that they are subjected to the milling action with the balls or rods. Thus, the additional milling means will act on particles or lumps of an intermediate size, that is, ones which are too large to pass through

the cylindrical screen but will protect the rollers from extremely large lumps or pieces which might cause damage thereto.

The preferred embodiment of our invention is illustrated in the accompanying drawings wherein similar characters of reference designate corresponding parts and wherein:

Figure 1 is an end elevational view of a screening mill constructed according to our invention.

Figure 2 is a horizontal sectional view taken substantially along line 2—2 of Figure 1.

Figure 3 is a vertical transverse sectional view taken through the mill.

Figure 4 is a detail in perspective of the sizing and feeding means which controls the feed of material to the crushing rollers.

Figure 5 is a perspective view, partly cut away, of our mill.

Figure 6 is a schematic view in perspective illustrating the driving system for the various parts of the mill.

Figure 7 is a diagrammatic view illustrating one use of the mill.

With reference to the drawings, the mill comprises the screening cylinder 1 which has the imperforate annular ends 2 and 3 and the perforated cylindrical wall 4. The perforations 5 in the wall 4 are of selected size to permit discharge of particles which have been reduced to a proper maximum size. The cylinder 1 is supported for rotation by at least two pairs of cradling rollers 6 which are carried by shafts 7 supported by the frame structure 8. Preferably the mill is enclosed within a housing 9 attached to the frame 8. The cylinder 1 is provided at circumferentially spaced points around its interior with longitudinally extending baffles or lifting plates 10 which serve to lift the material to be pulverized from the bottom of the cylinder and aid in the tumbling action. Within the cylinder 1, a plurality of the balls or rods 11 are provided in the usual manner. As is well understood, the tumbling action of the balls and material is usually the sole means relied upon in a mill of this type to grind or pulverize the material.

In order to effectively speed up the pulverizing action, we provide additional milling means within the cylinder 1 to reduce some of the larger particles in size so that the tumbling action of the balls and rods can quickly and effectively further reduce the particles to a maximum size so that they can pass on through the cylindrical screen.

This additional milling means takes the form of a pair of crushing rollers 12 which are disposed

within the cylindrical screen 1 and extend longitudinally thereof substantially at the center thereof. As shown in Figure 3, these rollers 12 are in contact with each other substantially at the axis of the cylindrical screen 1. The trunnions 13 of the rollers, as shown best in Figures 1 and 2, extend through the large central openings 2a and 3a provided within the annular end plates 2 and 3. These trunnions 13 are carried by bearings supported by the frame 8. The bearing structure at each end of the rollers 12 comprise the bearing blocks 14 in which the trunnions 13 are rotatably mounted. These bearing blocks 14 are slidably mounted in a transversely extending guide 15 supported by a cross member of the frame 8. A spacer 16 is also slidably mounted between the bearing blocks 14 in the guide 15 and may have shims 17 associated therewith for accurately positioning the two rollers 12 relative to each other. A compression spring 18 adjustable by means of a screw 19 may also be associated with the guide 15 and serves to move one of the rollers 12 towards the other with resilient pressure. The rollers 12 preferably do not actually contact but are spaced a slight distance apart depending upon the size of particles to be produced.

In order to prevent extremely large lumps of material from reaching the rollers 12 which might cause excessive wear or damage thereof, we provide the feeding and sizing unit 20. This unit 20 is in the form of a surge bin or hopper having the sidewalls 21 which converge at their lower edges towards each other to form the discharge slot 22. The wide upper or inlet top portion of the hopper is covered with arcuate bars 23a which are substantially parallel with the periphery of cylinder 1 and which are disposed in spaced relationship along the length of the hopper. The ends of the bars 23a are welded or otherwise secured to the upper edges of the hopper walls 21 and the space 23 between each adjacent pair of bars is of selected width to permit the passage of particles or lumps of a certain size. This size will be an intermediate size which is too large to pass through the openings 5 in the cylindrical screen but which are not sufficiently large to cause damage to the rolls 12.

In order to control the discharge of material from the hopper unit 20 we provide a longitudinally extending roller 24 which extends the complete length of the slot 22 and almost fills such slot. This roller serves as a feeder and agitator. An angle member 25 is mounted on each side of the hopper unit at the lower portion thereof adjacent the discharge slot thereof. One of these angle members has its inner edge 26 closely adjacent the roller 24 while the other has its edge 27 spaced from the roller. This angle member carries an adjustable gauge plate 28 which will control the amount of material discharged by the roller 24 through the slot 22. This gauge plate 28 is adjustable by the screws 29 carried by the angle 25 on which the plate is supported. The size of the particles which are fed from the hopper is determined by the spacing of the bars 23a and the amount is determined by the adjustment of the plate 28.

The material discharged from the hopper through the slot 22 will drop down between the rollers 12 and will be crushed thereby into particles of proper size. These particles are preferably of such a size that they will pass through the openings 5 and the cylindrical screen 1. Each of the angle members 25 further carries a scraper

plate 30 which is maintained in contact with its associated roll 12 by means of spring members 31 associated with each plate and the pivot rod 32 which is carried by lug 33 provided on angle members 25. The rolls 12 rotate towards each other as indicated in Figure 3 and with the plates 30 arranged as indicated, they scrape the surfaces of the rolls clean.

In order to feed the material to be broken up into the cylindrical screen 1, a supply chute 35 is provided at each end of the mill. These chutes 35 lead from a source of supply through the openings 2a and 3a in the respective end plates 2 and 3. For receiving the material discharged through the bottom of the cylindrical screen 1, a flared chute or hopper 36 is provided which extends up around the lower portion of the screen 1.

In the operation of this mill, the heavy material to be broken up is supplied within the cylinder 1 which will contain the balls or rods 11. The cylinder is rotated and the material will be broken up by the tumbling action in the usual way. Any particles which are sufficiently small will drop through the openings 5 of the screen 1 into the chute 36. Some of the larger lumps or pieces will be picked up by the baffles 10 and will eventually be deposited on the screen or grill formed by the rods 23a. The extremely large lumps will not drop through the spaces 23 but if the lumps are sufficiently small to drop through such spaces, they enter the hopper of the unit 20. From this hopper the lumps or pieces will be fed through the slot 22, under the control of the agitating and feed roll 24, to the crushing rolls 12. The roll 24 will prevent bridging or jamming of the material in the hopper of unit 20 and the adjustment of the plate 28 will control the amount of the material fed to the rolls 12. The rolls 12 will have their bearings 14 so spaced apart that the proper spacing of the rolls will result which will determine the size of the particles produced by the crushing action. This size should be sufficiently small to permit the crushed particles which drop on the bottom of the screen 1 to pass through the openings 5. However, if it happens that some of the particles which pass through the rollers 12 are larger or caked, they will be subjected to the tumbling action in the screen 1 which will reduce them. The balls or rods not only serve to break up the material but also keep the inner surface of the screen 1 clean.

The driving mechanism for the mill is illustrated in Figure 6. The shafts 7 are provided with sprockets 36 at one end around which a chain 37 passes. This chain also drives a sprocket 38 on the end of the roller 24. The chain 37 is positively driven by means of a sprocket 39 carried on a drive shaft 40. This drive shaft 40 is driven by an electric motor 41 through the medium of a belt drive 42. Thus, the cylinder 1 and shaft 24 are driven positively simultaneously. The rolls 12 are driven at the same time by means of a chain drive 43. This drive includes a driving sprocket 44 keyed on shaft 40 and driving sprockets 45 keyed on the ends of the shafts 46 which carry the rolls 12.

This mill will have various applications but in Figure 7 we have illustrated diagrammatically one application of it. In this figure, the mill is indicated generally at M. It is shown associated with a screening and crushing unit of the type which may be provided at a stone quarry such as a limestone quarry. The equipment includes the rough crusher A from which the material is carried to a second screening and crushing unit B

5

and then to a third crushing and screening unit C. In these various crushing and screening units, the material is successively reduced in size and separated. The finer material discharged from the unit C will be conducted by the trough 35 to the mill M. This material, for example, may be lime material which is too small for use as road aggregate or for similar usages and which includes various sizes of the smaller material. Our mill M may be employed to further reduce this material so that it will be in sufficiently small particles to serve as agricultural lime.

It will be apparent from the above description that we have provided a novel type of mill which although it is of the ball or rod mill type includes additional means for crushing or reducing the material. The additional means in the form of crushing rolls is protected by the sizing and feeding unit.

Various other advantages will be apparent.

Having thus described our invention, what we claim is:

1. A screening mill comprising a rotatable cylindrical screen having a single compartment for receiving material to be broken up and having balls or rods therein, means for supplying material into the screen, baffles on the wall of the screen which serve to lift some of the material to the top of the screen, a pair of crushing rolls supported within this screen substantially at the axis thereof, and extending parallel to the axis

6

and a single sizing and feeding unit supported above the rolls for receiving material lifted by the baffle and feeding it between the rolls, said sizing and feeding unit comprising a hopper covered with a grill which permits particles of a predetermined maximum size to enter the hopper, said hopper having a lower end with a discharge slot therein, and means for varying the width of said slot.

10 2. Apparatus according to claim 1 wherein a feed roll is disposed within said slot and including means which drives the feed roll simultaneously with the screen cylinder and the crushing rolls.
